INVENTOR.

Fay T. Rodgers

by J. W. Weatherford
ATTORNEY.

UNITED STATES PATENT OFFICE.

FAY T. RODGERS, OF MEMPHIS, TENNESSEE.

REFRIGERATOR.

Application filed July 18, 1925. Serial No. 43,135.

To all whom it may concern:

Be it known that I, FAY T. RODGERS, a citizen of the United States, residing at Memphis, in the county of Shelby and the State of Tennessee, have invented certain new and useful Improvements in Refrigerators, of which the following is a full, clear, and exact description, such as will enable anyone skilled in the art to make and use the same.

This invention relates to refrigerators having ice containers arranged in either or both ends thereof, and has especial relation to the shape, arrangement and disposition of the ice containers within the refrigerator.

It is of extreme importance in refrigerators, that advantage be taken of every opportunity to promote the circulation of air in contact with the cooling medium, usually ice, carried in these containers, and numerous attempts have been made and are being made, to devise means whereby this may be accomplished. Heretofore in attempting to promote this circulation, tubes have been passed through the containers in an endeavor to give more surface of contact of the air with the refrigerant.

The objects of my invention are,

First, to provide means whereby a large surface area may be exposed to the air in the refrigerator.

Second, to provide means for inducing circulation of the air in contact with the surface of the refrigerant container and of the refrigerant, and

Third, to reduce the bulk and weight of the refrigerant, that must be handled at any one time.

I accomplish the first and third of these objects by subdividing the refrigerant container into a plurality of containers, the sum total of which will make up the necessary size of container, and by separating these containers so that the air may circulate around, over, under and between them; and I accomplish the second of these objects by disposing these containers at an angle or with a certain amount of dip from the horizontal whereby circulation of the air will be induced by gravity.

In the drawings:

Fig. 1 is a sectional elevation on the line I—I of Fig. 2, looking in the direction of the arrow showing the arrangement of a plurality of containers within one end of a refrigerator casing.

Fig. 2 is a sectional elevation on the line II—II of Fig. 1.

Referring now to the drawings, in which the various parts are indicated by numerals, 1 is a refrigerator casing, preferably double walled, with insulating material therebetween. 2, 3 and 4 are refrigerant containers slidably mounted within this casing on angle iron supports 5, which supports extend from the front to the back of the casing. 6 is a door through which access may be had to these containers, and also through which each of them may be removed for refilling or other purposes as may be desired. 65 7 are handles for withdrawing the container. 8, 9 and 10 are drain valves the location of which determines the water level in the various containers, where, as is ordinarily the case, ice is used as the refrigerant. 75

The drain valve 8 is disposed to drip into a funnel 11 and this funnel again into a second funnel 12, which latter funnel drains into a water pan 13. The drip valve 9 is connected to the funnel 11 and the drip valve 10 to the funnel 12. 14 is an overflow pipe for the pan 13. This overflow pipe is covered by an inverted cup 15 having notches 16 through which water from the pan 13 may enter, thus forcing water 85 to be drawn off from the lower part of the pan rather than from the surface thereof.

The angle iron guide- or slide-ways 5 for the containers 2 and 3 are so placed that the side of the container which is adjacent the 90 end of the casing 1 is lower than the side which is disposed toward the open part of the refrigerator, and these two containers are preferably each made with its top parallel to the bottom, thus disposing these containers so that each is downwardly inclined toward the end of the refrigerator.

The container 4 and the guide- or slide-ways therefor may be similarly disposed but I prefer to place the guide-ways for this container on the same level and to make that edge of the container which is to be disposed adjacent the end wall of the refrigerator lower than the other side, so that the top of this container will be parallel to the bottom of 105 the container above it, although the bottom of it is horizontally disposed. These containers and the pan beneath the lower one are preferably disposed with the bottom of one uniformly spaced away from the top of 110 the next lower one and these spaces are also preferably of equal size.

In use, the containers are withdrawn from the refrigerator and filled with ice, or ice and salt if it be so desired, and then replaced in the refrigerator. Being subdivided, and comparatively small, they may be much more readily handled than a single bulky container could be. After being replaced in the refrigerator the warmer air along the top of the refrigerator is cooled and drops downward being caused by the inclination of the containers to set up a circulating movement toward the end of the refrigerator casing, and thence downward and thence away from the end of the said casing, and over the surface of the water in the drip pan 13 into the body portion of the refrigerator. Likewise the air between the various containers is similarly cooled and a similar circulation set up.

It will of course, be evident that while I have shown three containers, two only may be used: or if the refrigerator is a large one, even more containers than shown, may be used, the angle of inclination may be varied and various details of construction may be modified as may be necessary or advantageous.

Having now fully described my invention, what I claim is:—

1. Means for cooling a refrigerator, comprising a plurality of refrigerant containers, disposed one above the other and spaced apart, the bottom of any container and the top of the container below being downwardly inclined in substantially parallel planes whereby inclined channels are provided to induce air flow between said containers. 30

2. Means for cooling a refrigerator, comprising a plurality of refrigerant containers, disposed one above the other and spaced apart, the bottom of any container, and the top of the container below being downwardly inclined in the same direction, whereby inclined channels are provided to induce air flow between said containers. 40

3. Means for cooling a refrigerator, comprising a plurality of refrigerant containers, near one end of the refrigerator, disposed one above the other and spaced apart, the bottom of any container and the top of the container below being downwardly inclined, in substantially parallel planes, toward the adjacent end of the refrigerator casing, whereby inclined channels are provided to induce air flow between said containers. 50

In testimony whereof I have hereunto set

FAY T. RODGERS.
